(57) **CLAIM**

The ornamental design for a wine stopper, as shown and described.

DESCRIPTION

FIG. 1 is a front, right, and top perspective view of a wine stopper, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is another front, right, and top perspective view of the wine stopper, wherein the wine stopper is in an usage state. The broken lines shown in the drawings are included for the purpose of illustrating portions of the wine stopper that form no part of the claimed design.
